UNITED STATES PATENT OFFICE.

CHARLES K. HUTHSING, OF ST. LOUIS, MISSOURI.

FIRE EXTINGUISHER.

Application filed March 12, 1923. Serial No. 624,501.

This invention relates to fire extinguishers of the kind that comprise a manually-operable pump for discharging the liquid contents of the container through a hose.

One object of my invention is to provide a fire extinguisher of the type referred to that is equipped with a novel means for locking the plunger of the pump in such a way that the hand piece on the upper end of 10 said plunger can be used as a handle for carrying the extinguisher.

Another object is to provide a fire extinguisher of the type referred to in which the cylinder or barrel of the pump is provided at its upper end with a part arranged 15 on the outside of the liquid container of the extinguisher and equipped with a hose connection, thereby simplifying the construction and reducing the cost of manufacturing the extinguisher, as well as making 20 it possible to have an inclined outlet, as distinguished from a right-angular outlet from the pump barrel to the discharge hose.

Figure 1 of the drawings is a vertical sectional view of a fire extinguisher constructed in accordance with my invention.

Figure 2 is a perspective view of the removable member in the lower end of the pump barrel that carries the strainer or 30 screen and the cage for the inlet valve of the pump; and

Figure 3 is a perspective view of the hand piece on the upper end of the plunger of the pump.

Referring to the drawings which illustrate the preferred form of my invention, A designates the liquid container of my improved fire extinguisher, which preferably consists of a cylindrical-shaped member provided with a bottom 1 and a dome-shaped top 2, B designates a vertically-disposed pump cylinder or barrel arranged inside of the liquid container A and provided at its upper end with a part C arranged on the 40 upper side of the top 2 of the container A and provided with a hose connection 3, D designates the hollow plunger of the pump which projects through a stuffing box E carried by the part C on the pump barrel, 45 said plunger being of conventional form and provided at its lower end with a piston having a reduced portion of less diameter than the pump barrel so as to permit the liquid in the plunger to escape from same into the 50 barrel through ports 20 in the reduced portion of the piston, F designates a hand

piece rigidly connected to the upper end of said plunger and G designates a hose attached to the hose connection 3 at the upper end of the pump barrel.

In order that the hand piece F on the plunger of the pump may be used as a handle to carry the container means is provided for locking said hand piece to the stuffing box E. In the form of my invention herein illustrated the means referred to consists of a pin 4 that is adapted to be inserted through aligned holes in lugs 5 on the stuffing box E in such a way that it is positioned in a slot or groove 6 in the hand piece F, as shown in Figure 1, thereby preventing the pump plunger and the hand piece F thereon from turning or reciprocating relatively to the pump barrel or to the liquid container A of the extinguisher. 75 When it is desired to use the pump the pin 4 is withdrawn from engagement with the lugs 5 and the slotted portion of the hand piece F, thereby permitting the pump plunger D to be reciprocated in the barrel or 80 cylinder B of the pump. The locking device 4 is preferably connected to a chain or other flexible element 7, so as to prevent it from becoming lost when it is not in use, the chain 7 being herein illustrated as connected to a handle 8 on the container A and secured to a filling plug 9 in the top 2 of the container through which the liquid is introduced into the container A.

By providing the member C at the upper 90 end of the pump barrel with a hose connection 3 that is arranged on the outside of the liquid container A, I overcome the necessity of forming a hole in the side wall of the liquid container, and another advantage that results from such a construction is that the duct 10 that connects the pump barrel with the hose G can be arranged in an upwardly-inclined position instead of at right angles to the pump barrel. In constructing the extinguisher the pump can be assembled as one complete unit and then inserted through a hole in the top 2 of the liquid container A, and then permanently combined with said container by screws or other suitable fastening devices 11 that pass through the portion of the member C which bears upon the top 2 of the container.

The pump barrel B is provided at its lower end with a removable member H that is equipped with a strainer or screen 12 and

also with a cage for a ball check valve 13 that controls the passage of the liquid from the container A into the barrel or cylinder of the pump. In the form of my invention herein illustrated the strainer 12 is formed by a disk-shaped, perforated element that is substantially flat and set flush in the lower end of the member H and said member is provided with an externally screw-threaded portion 14 that is screwed into the lower end of the pump barrel B, as shown more clearly in Figure 1. The cage for the ball check valve 13 is formed by a pair of integral lugs 15 that project upwardly into the pump barrel and each of which is provided with a slot or bifurcation 16, as shown in Figure 2, thus forming four upwardly-projecting fingers that form a cage for the check valve 13. Usually the member H is formed from a casting, and after the check valve 13 has been positioned between the upwardly-projecting lugs 15 on said member, the fingers formed by the vertical slots in said lugs are bent inwardly 25 slightly over the check valve, as shown in Figure 2, so as to limit the upward movement of said check valve relatively to its seat. Such a construction is inexpensive to manufacture, and as the screen or strainer 12 is positioned in close proximity to the bottom 1 of the container A, practically all of the liquid in said container can be pumped out of same by operating the plunger of the pump.

The liquid container A is provided at its lower end with a combined foot piece and handle I that consists of a loop or bale equipped with an angularly-disposed part or crank portion 17 which is surrounded by a bracket 18 on the container. When the device I is not in use it can be folded up

against the side of the container, as shown in broken lines in Figure 1, and when the pump of the extinguisher is being used, said device I can be swung downwardly into the position shown in full lines in Figure 1, so as to serve as a foot piece on which the user can exert pressure with his foot so as to hold the liquid container A stationary when the plunger of the pump is being reciprocated. Owing to the fact that the device I is provided with an angularly-disposed part or crank portion 17 which turns in a bearing or bracket 18 on the side of the container A, it is impossible for said device I to swing into a position under the bottom of the container or under the lower edge of the container, and thus prevent the container from bearing evenly or resting squarely on the floor or other supporting structure on which it rests.

Having thus described my invention, what I claim as new and desire to secure by Letters Patent is:

In a fire extinguisher, a liquid container, a pump cylinder in said container provided at its upper end with a member arranged on the outside of the top of said container and provided with an integral hose connection, a stuffing box carried by said member, a pump plunger projecting upwardly through said stuffing box and provided with a hand piece that has a transversely-disposed portion in which a transverse slot is formed, integral, perforated lugs on said stuffing box arranged so as to embrace the transversely-disposed portion on said hand piece, and a removable locking pin that is adapted to be inserted through said lugs and positioned in the slot in said hand piece, for the purpose described.

CHARLES K. HUTHSING.
